US00D916065S

(12) **United States Design Patent** (10) Patent No.: **US D916,065 S**
(45) Date of Patent: **** Apr. 13, 2021**

(54) **MOBILE PHONE**

(71) Applicant: **Samsung Electronics Co., Ltd.**, Suwon-si (KR)

(72) Inventors: **Hyoungshin Park**, Seoul (KR); **Seungho Jang**, Seongnam-si (KR); **Dongkyun Kim**, Seoul (KR); **Seonkeun Park**, Seoul (KR); **Yunjin Kim**, Seoul (KR)

(73) Assignee: **Samsung Electronics Co., Ltd.**, Suwon-si (KR)

(**) Term: **15 Years**

(21) Appl. No.: **29/688,572**

(22) Filed: **Apr. 23, 2019**

Related U.S. Application Data

(63) Continuation of application No. 29/656,175, filed on Jul. 11, 2018, now Pat. No. Des. 865,733.

CLAIM

We claim the ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The evenly-dashed broken lines in the figures depict portions of the mobile phone that form no part of the claimed design.

The dot-dash broken lines in the figures represent a boundary of the claimed design and form no part thereof.

1 Claim, 6 Drawing Sheets
